[57] CLAIM

The ornamental design for an engine oil container holder, as shown and described.

DESCRIPTION

FIG. 1 is a front, top and right side perspective view of an engine oil container holder showing my new design, the broken-line disclosure of an engine oil container being for illustrative purposes only and forming no part of the claimed design;

FIGS. 2 and 3 are respectively front and rear elevational views thereof;

FIG. 4 is a side elevational view thereof, the side opposite being a mirror image; and,

FIGS. 5 and 6 are respectively top and bottom plan views thereof.
